UNITED STATES PATENT OFFICE.

WINFIELD HANCOCK YOST, OF MONTREAL, QUEBEC, CANADA, ASSIGNOR TO RODGER
BALLAST CAR COMPANY, OF CHICAGO, ILLINOIS, A CORPORATION OF MAINE.

CAR CONSTRUCTION.

1,251,609.

Specification of Letters Patent.

Patented Jan. 1, 1918.

Application filed June 4, 1914. Serial No. 842,900.

To all whom it may concern:

Be it known that I, WINFIELD HANCOCK Yost, a citizen of the United States, residing in the city of Montreal, Province of Quebec, Dominion of Canada, have invented certain new and useful Improvements in Car Construction; and I do hereby declare that the following is a full, clear, and exact description of the same.

10 This invention relates particularly to cars adapted to have a plow passed therethrough and known as "ballast" cars and has for an object to improve the general construction of cars of this type and specifically to provide a novel hinge connection and support for convertible floor sections and provide means for accommodating and protecting the door locking gear.

15 The above with further objects and advantages will be hereinafter more fully described and particularly pointed out in the claims.

20 For full comprehension, however, of my invention reference should be had to the accompanying drawings forming a part of this specification in which similar reference characters indicate the same parts and wherein;

25 Figure 1 is a view illustrating one half of the car in end elevation, partly broken away, and half in transverse section.

30 Fig. 2 is a detail perspective view looking inwardly at one side of the bolster stake;

35 Fig. 3 is a detail section of the hinge connection between the floor and convertible floor sections, taken on line 3—3 Fig. 7 with the floor sections lowered;

40 Fig. 4 is a view similar to Fig. 3 with the floor portions raised;

45 Fig. 5 is an enlarged perspective view of the member forming the hinge connection illustrated in Figs. 3 and 4;

Fig. 6 is a vertical section on line 6—6 Fig. 1;

50 Fig. 7 is a plan view partly broken away of a portion of the car, the stakes being in horizontal section;

Fig. 8 is a vertical section on line 8—8 Fig. 7;

55 Fig. 9 is an elevation of a portion of the car side.

The underframe of my improved car comprises as usual a center sill 2, end sills 3, side sills 4, bolster 5 with top plate 6, cross-beams 7 with top plate 7a,

The floor which is supported by the bolsters, cross-beams, etc., includes a permanent middle section 9 spaced from the sides of the car and convertible side floor sections 11 extending between the bolsters and cross-beams and forming a continuation of the floor to the sides of the car, such convertible sections being hinged to the permanent floor and adapted to assume a downwardly inclined position and form, with fixed portions 12, discharge aprons as shown in Fig. 3, this construction of the floor not being new in the present instance.

The permanent floor section is bordered at each side by a Z-bar 10, the top flange of which extends outwardly from the floor preferably level with the latter to form a part of the same and constitute a wear plate for a plow when the latter passes through the car.

To provide a simplified and more readily applied hinge connection for the convertible sections, the batten-like reinforcing strips 13 thereof are extended beyond the inner edges of the sections and turned at an angle to their main length to form hooks which are passed through apertures or slots 14 in the webs of the Z-bars 10, the extended ends of the strips being sufficiently loose in the slots to permit of the swinging of the sections 11 but held against accidental detachment by the hooked ends. The movement of the hooked ends, as the convertible portions swing, is accommodated in recesses 15 formed by cutting away portions of the permanent floor section just behind the slots in the Z-bars and when up the sections 11 are conveniently supported and readily hooked to the car structure at their free ends as will be presently described.

In the preferred construction the strips each consists of a single piece of metal, one longitudinal side margin 13 of which is adapted to be fastened flat upon the underside of the floor section 11 while a part 16 of the other longitudinal side margin is bent at an angle to the margin 13 to form a reinforcing strip proper. The remaining part 17 of the bent margin is folded over flat against the adjacent portion of the margin 13 and such doubled part bent transversely of and at an angle to the strip to form a hook 18, the folded part 17 making the hinge portion more rigid and reinforcing the same where it engages with the edges of 110

the slot in the Z-bar 10. The end of the side margin 13 opposite to the hook may be extended and bent transversely of and at an angle to the main length to constitute a hook 19 projecting downwardly from the section and adapted to engage with a loop or similar member such as shown in the drawings wherein a plate 11^a having an offset portion 11^b is secured at a convenient point to the car structure adjacent the outer edge of the convertible section, the offset portion 11^b providing a space between the plate and car for the reception of the hook 19.

With this form of hinge connection the use of hinge pins, cotters and other small parts is avoided while the connection is more quickly made than heretofore by simply inserting the hooks in the slots 14. The hooks 18 are loose within the apertures 14 and the strips extend a sufficient distance beyond the edge of the convertible sections to enable the latter to move outwardly with respect to the permanent floor so that when in their up position such sections can be tilted and moved outwardly to engage the hooks 19 over the plate 11^b thus readily supporting the sections and securing the same against accidental movement out of their raised position. The inner edges of the convertible sections are at all times located beneath and are depressed at 11^c for the reception of the overhanging sides of the floor constituted by the outwardly extending flanges of the Z-bars 10 and as the hinge connections are also overhung any liability of the material carried by or discharging from the car interfering with the free working of such connections is avoided.

The corner stakes and cross-beam side stakes are indicated at 20 and the bolster side stakes at 20^a, such stakes being secured to the car by means which include longitudinal vertical gussets 22 and although the stakes are shown as constructed and braced in a novel manner said construction and bracing do not form part of my invention, but are included and claimed in U. S. Patent application Serial No. 842,922, Dorey, filed June 4, 1914.

50 The corner and cross-beam stakes carry top rails 42 to which doors 43 are hinged, such doors extending down below the level of the flooring and closing against the before mentioned fixed portions 12. The doors 55 are locked by means of shafts 44 which are worked within slots 45 in the stakes by chains 46 and ratchet mechanism 47 the chains each being attached to the stake preferably by means of an angle bar 48 extending across the stake and having one flange extending outwardly from the stake and having the chain attached thereto, the slots 45 extending inwardly at the bottom. To 60 avoid interference between the doors and chains the free edges of the former are

tapered as at 49 thus providing ample accommodation for uninterrupted movement of the chains as illustrated in Fig. 9.

To avoid the clogging of the door locking gear by the discharging material and to 70 otherwise protect such gear shields are provided which are accommodated by the tapering doors and located between the discharge openings of the car and that side of the chains 46 adjacent to such openings. The 75 shields preferably extend outwardly from the longitudinal gussets 22 and are disposed as close as possible to the chains, the shield at each bolster stake being formed by an angle iron 50 having one flange riveted 80 to the gusset and the other flange 51 extended outwardly from the latter to a point adjacent the shaft, such flange 51 extending downwardly from a point close to the outwardly extending flange of the bar 48 to 85 near the bottom of the stake, and having its outer edge conforming to the inner edge of the slot 45 in the bolster stake. Wherever possible, such as at the cross-beam stakes, the gear shields are formed by providing 90 the gussets 22 with outwardly extending flanges 52.

What I claim is as follows:

1. In a ballast car, a floor spaced from the sides of the car, plates secured to the 95 car, spaced from the edges of the floor and having offset portions, convertible sections extending from the edges of the floor and members upon the convertible sections adapted to hook over such offset portions, 100 said plates being stationary with relation to the car.

2. In a ballast car, an underframe, a floor upon the underframe and spaced from the sides of the car, floor sections extending outwardly from the floor and movable up and down with relation thereto and ledges located above the underframe, adjacent to the outer edges of the sections and adapted to have the latter, when up, rest thereon, said 105 ledges being stationary with relation to the car.

3. In a ballast car, an underframe, a floor above the underframe and spaced from the sides of the car, a convertible floor section 115 movable up and down and bodily outwardly with relation to the floor and a ledge above the underframe and normally out of the path of the swinging door and adapted to have the section when moved outwardly, 120 rest thereon, said ledge being stationary with relation to the car.

4. In a ballast car, a floor formed with an aperture, a convertible floor section, a strip upon the convertible floor section and 125 extending beyond the inner side of the latter, the extended end of the strip being bent and passed through said aperture.

5. In a ballast car, a floor, a metallic member bordering the floor and having aper- 130

tures therein, convertible floor sections, strips upon the convertible floor sections and extending beyond the inner edges of the latter, the extended end of each strip being 5 bent at an angle to its main length and passed through one of said apertures.

6. In a ballast car, a floor, a convertible floor section and means for connecting the convertible section to the floor, comprising a 10 strip formed of a single piece of metal, the first longitudinal side margin of which is fastened upon the underside of the convertible section and the second longitudinal side margin bent at an angle to the first margin 15 for a part of its length and then folded over flat against such first margin, the end of the doubled part of the strip being bent transversely of and at an angle to the main length of the strip.
- 20 7. In a ballast car, side stakes, a top rail supported by the stakes, a door extending between the stakes and hinged to the top rail and door locking mechanism comprising a shaft and a chain attached at one end to 25 the shaft and at the other end to the car at

a point above the lower edge of the door when closed, the lower corner of such door being cut away to accommodate the chain.

8. In a ballast car having a side discharge opening, a stake having a slot therein, a 30 door for closing such opening, a shaft in said slot and adapted to lock the door in closed position, an angle bar extending across the stake and having one flange projecting outwardly from the latter, a chain 35 attached at one end to said projecting flange and at the opposite end to the shaft, a shield extending outwardly from the car to a point adjacent the shaft, the shield extending downwardly from a point close to said projecting flange and the outer edge of such shield conforming to the inner edge of the slot in the stake.

In testimony whereof, I have signed my name to this specification, in the presence 40 of two subscribing witnesses.
